UNITED STATES PATENT OFFICE.

JOHN D. RENSHLER, OF FINDLAY, OHIO.

BURIAL-CASKET.

No. 823,741.

Specification of Letters Patent.

Patented June 19, 1906.

Application filed April 28, 1906. Serial No. 314,215.

To all whom it may concern:

Be it known that I, JOHN D. RENSHLER, a citizen of the United States of America, and a resident of Findlay, county of Hancock, State of Ohio, have invented certain new and useful Improvements in Burial-Caskets, of which the following is a full and clear specification, reference being had to the accompanying drawings, in which—

10 Figure 1 is a perspective view showing the casket opened. Fig. 2 is a side elevation of the casket closed. Fig. 3 is a transverse section of the casket closed. Fig. 4 is a perspective view in detail of a part of the drapery-frame swung to the front edge of the upper section, and Fig. 5 is a detail vertical section showing one of the fastening devices.

15 The object of this invention is to improve that type of burial-caskets known as the "Dav-
20 enport," in which the shell or body is adapt-
ed to open in such manner as to give to the
casket the appearance of a sofa, the upper or
cover section serving as a sort of canopy, as
more fully hereinafter set forth.

25 To the accomplishment of this object and
such others as may hereinafter appear the in-
vention consists of the parts and combination
of parts hereinafter fully described, and par-
ticularly pointed out in the appended claim,
30 reference being had to the accompanying
drawings, forming a part of this specification,
in which the same reference characters desig-
nate like parts throughout the several views.

Referring to the drawings annexed by ref-
35 erence characters, A designates the lower or
main section of the casket, which consists of
the entire back wall and bottom and narrow
portions of the top and front walls, together
with the triangular portions a' of the end
40 walls. The upper or cover section B con-
sists of the main portion of the top, the main
portion of the front wall b, and the triangular
sections b' of the end walls. The upper sec-
tion is hinged at G to the top strip of the
45 lower section, so that when the upper section
is swung up and back the top part of the up-
per section will be substantially a continua-
tion of the main shell and the front wall b
will project horizontally forward. Hinged
50 supporting-braces or props C are arranged to
support the upper section in its raised posi-
tion, these supports lying within the casket,
so that when the casket is closed they will be
entirely hidden from view.

55 As shown in Figs. 1 and 2, the handle at
the front side is attached to the front wall b

of the upper section, and a series of three
strong fastening devices F are employed to
lock the front wall b down on the upper edge
of the portion of the front wall attached to 60
the bottom. Each of these fasteners con-
sists of a plate fastened by screws to the
lower portion of the front wall, where it will
be obscured by the base-molding a. Hinged
65 to this lower plate is a plate which is pro-
vided with a vertical slot, through which the
winged head f' of a turn-button f is adapted
to pass, the wing on the button serving when
the button is turned to lock the hinged sec-
70 tion of the fastener to the front wall b. These
series of fasteners form a strong and reliable
connection between the upper section and
the base, so that the handle may be attached
75 to the upper section. The hinged sections
of the fasteners when the casket is opened
may be swung down upon the face of the
base-molding a, where they will be out of the
way. These fastening devices are of course
80 to be made ornamental, so that they will not
detract from the appearance of the casket. 80

Hinged by means of suitable hooks and
eyes d to the extreme front edge of the front
wall b is a depending frame D, consisting,
preferably, of a series of separated wings or
plates. This frame is adapted to carry the 85
drapery that is to be swung from the front
edge of the top section when the casket is
opened, thereby greatly adding to the ap-
pearance of the casket. The sectional ar-
rangement of the frame is desirable in that it 90
permits the drapery to be festooned the
length of the casket and suitable tassels ar-
ranged between the festoons. About mid-
way the length of this swinging frame is a de-
pending lever E, having an eye at its lower 95
end, which lever when the casket is closed is
employed to swing the drapery-carrying
frame back and up against the inner face of
the front wall b, where the frame will be held
100 by the eye of the lever E catching into a suit-
able hook e, carried by said wall b. In this
way the drapery may be neatly and care-
fully folded back out of the way when the
casket is closed, so that it will not interfere
105 with the ready closing of the casket.

What I claim, and desire to secure by Let-
ters Patent, is—

In a casket of the type set forth, the combi-
nation of a main section, an upper section
hinged thereto at its rear edge and consisting 110
of the top and the front wall of the casket,
this front wall being adapted to extend hori-

zontally outward when the casket is open, a
drapery-carrying frame hinged to and de-
pending from the front edge of the said for-
wardly-projecting front wall, and means for
5 fastening said frame to the inner face of said
front wall when the casket is closed, substan-
tially as set forth.

In testimony whereof I hereunto affix my
signature, in the presence of two witnesses,
this 20th day of April, 1906.

JOHN D. RENSHLER.
